UNITED STATES PATENT OFFICE.

FRANK J. DYETT, OF ILION, NEW YORK.

TYPE-WRITING MACHINE.

No. 845,066.

Specification of Letters Patent.

Patented Feb. 26, 1907.

Application filed July 16, 1904. Serial No. 216,790

To all whom it may concern:

Be it known that I, FRANK J. DYETT, of Ilion, in the county of Herkimer and State of New York, have invented a certain new and useful Type-Writing Machine, of which the following is a specification.

My invention relates to escapement mechanism for type-writing machines, and particularly to the construction and arrangement of the detents coacting with the escapement ratchet-wheel and of the means for supporting and operating the detents; and said invention has for its object the production of a mechanism for the desired use which is particularly simple in construction and highly efficient in operation.

To this end the invention consists in the combination, construction, and arrangement of the parts hereinafter set forth, and pointed out in the claims.

In describing this invention reference is had to the accompanying drawings, in which like characters designate corresponding parts in all the views.

25 Figs. 1 and 2 are respectively elevation and plan of a portion of a type-writing machine equipped with one embodiment of my invention. Fig. 3 is a sectional view on line A A, Fig. 1. Figs. 4 and 5 are elevations, partly 30 in section, of portions of the devices shown in Fig. 1, the pivoted detent being illustrated in different positions. Figs. 6 and 7 are elevations of the oscillating member carrying the detents and the pivoted detent.

35 1 is a fragmentary part of the top plate or frame member of a type-writing machine, and 2 is a vertically-arranged frame member, here shown as a post or pillar suitably fixed, as by screws 3, Fig. 2, in a slot 4 in the plate 1 and projecting above and below said plate and provided with a laterally-extending offset portion 5 beneath the plate 1.

40 6 is a shaft which is journaled in an opening extending through opposite surfaces of the top or head of the frame member 2 and projects beyond said surfaces, its projecting ends being respectively provided with a pinion 7 and an escapement ratchet-wheel 8. The pinion 7 engages a rack-bar (not illustrated) on the carriage of the type-writing machine, normally prevents the carriage from being moved by a motor, as a spring, tending to advance the carriage for feeding the paper thereon, and when rotated step by step permits the carriage to advance correspond-

ingly. The ratchet-wheel 8 controls the rotation of the pinion 7 as in the common construction of escapement mechanism and is in turn controlled by means interposed between said wheel 8 and the keyboard of the type-writing machine.

In my invention the means for controlling the rotation of the ratchet-wheel 8 preferably comprises a rock-shaft 9, journaled in the offset portion 5 of the frame member 2 and extending parallel to the shaft 6 at one side of the vertical plane thereof, an oscillating member 10, fixed to one end of the shaft 9, opposing detents 11, 12, carried by the member 10, an arm 13, fixed to the other end of the rock-shaft 9, and means for operating the arm 13.

The oscillating member 10 is illustrated as having angularly-arranged portions, one being substantially horizontal and pivoted at 75 its free end by the rock-shaft 9, which forms a support for said member, and the other being extended upwardly at one side of the plane of the escapement-wheel 8 and provided in proximity to its free end with opposite upwardly-diverging arms or branches 14, 15, arranged substantially concentric with the escapement-wheel 8 and the pivoted detent 12. It thus follows that the axis of the oscillating member 10 is arranged at one side 85 of a line, as 16, Fig. 4, extending through the axis of the escapement-wheel 8 at substantially a right angle to a line, as 17, passing through said axis and the engaging face of the detent 11. The arm 14 is formed near its 90 upper or free end with an offset portion 18 movable in the plane of the wheel 8 and having its edge opposed to said wheel provided with a fixed lateral extension forming the detent 11. The upper or free end of the arm 15 is provided with a lateral extension 19 in the plane of the escapement-wheel 8. Said oscillating member 10 also carries stops spaced a distance apart, one, 20, being arranged at the base of the arm 14 and the other, 21, being 95 supported by the lateral extension 19 and adjustable therein toward and from the stop 20.

The detent 12 is shown as pivoted substantially in alignment with the axis of the escapement-wheel 8 to the upper or free end of 105 a part of the oscillating member 10, arranged substantially midway between the branches 14, 15 and as comprising a radial arm interposed between the member 10 and the escapement-wheel 8 and pivoted at one end, 110

and a segmental head opposed to and slidably engaging the branch 15 and having an offset portion 22 movable in the plane of the wheel 8 and provided with the face of said detent which engages the escapement-wheel 8. Said segmental head of the detent 12 is movable between the stops 20 21, and its end edges engage with said stops for limiting the movement of the detent 12 on its pivot relatively to the oscillating member 10. A suitable spring 23 tends constantly to force the detent 12 into engagement with stop 21.

The arm 13 extends in a horizontal plane, is fixed at one end to the rock-shaft 9, and is connected at its other end to a spring 24 and a link 25. The spring 24 normally engages the oscillating member 10 with a suitable stop-pin 26, and the link 25 depresses the free end of the arm 13 against the action of the spring 24 and is connected to the universal bar of the type-writing machine, so that said arm 13 is operated whenever the universal bar is depressed.

In the drawings I have shown my escapement mechanism as connected to the means for advancing the ribbon step by step seen in my pending application, Serial No. 204,166, filed April 21, 1904, said means comprising ribbon-spools 27, a shaft 28 for rotating the ribbon-spools 27, clutch members 29 30 for connecting the shaft alternately to said spool, a ratchet-wheel 31, fixed to the shaft 28, a lever 32, pivoted intermediate of its ends to an arm 33, provided on the frame member 2, a spring 34 for retracting the lever 32, a pawl 35 depending from one end of the lever 32 and having its upper extremity pivoted to said lever and its lower extremity engaged with the ratchet-wheel 31, a ratchet-wheel 36 fixed to the shaft 6, a pawl 37 having its lower end pivoted to the other end of the lever 32 and its upper end engaged with the ratchet-wheel 36 and provided with a cam-face 38, and a knock-off pin 39 for engaging the face 38 and forcing the pawl 37 out of engagement with the ratchet-wheel 36. A spring 40 tends to hold the pawl 37 in engagement with the ratchet-wheel 36, and said pawl is provided intermediate of its ends with a slot 41, which receives the pin forming the stop 26 in order that said slot and pin may guide the pawl 37 in its movement.

A suitable ribbon-guide 42 is shown in operative position in Fig. 1, but as said ribbon-guide forms no part of my present invention it is thought unnecessary to describe the same herein.

To those skilled in the art it will be understood that as the shaft 6 rotates step by step it successively raises the pawl 37 and through the medium of the lever 32 correspondingly depresses the pawl 35 and advances the ratchet-wheel 31 and the ribbon-spools and that as the pawl 37 reaches the limit of its upward movement the cam-face 38 and

knock-off pin 39 cause to disengage said pawl from the ratchet-wheel 36, whereupon the spring 34 retracts the lever 32.

The operation of my escapement mechanism is as follows: The detent 12 engages the escapement-wheel 8 whenever the oscillating member 10 is in its normal position in engagement with the stop 26, as shown in Fig. 4. When the link 25 depresses the free end of the arm 13 against the action of the spring 24, the detent 11 is engaged with the wheel 8, and the detent 12 is then disengaged from said wheel, but no revolute movement of the shaft 6 is permitted, as said detent 11, engaged therewith, is fixed relatively to the oscillating member 10. Immediately upon the disengagement of the detent 12 from the ratchet-wheel 8 the spring 23 engages said detent with the stop 21. As soon as the arm 13 is released from the action of the link 25 the spring 24 raises the free end of said arm and returns the oscillating member 10 to its normal position in engagement with the stop 26, thus engaging the detent 12 with the escapement-wheel 8 and disengaging the detent 11 from said wheel. Immediately after the disengagement of the detent 11 from the wheel 8 the motor, as a spring tending to move endwise the carriage connected to the pinion 7, rotates this pinion, the shaft 6, and the ratchet-wheel 8, and also rotates against the action of the spring 23 the detent 12, engaged with the wheel 8. When the detent 12 has been revolved sufficiently to engage with the stop 20, rotation of the parts 6 7 8 100 12 ceases, and further movement of the carriage is prevented. The distance the escapement-wheel 8 turns at each operation of the arm 13 may be more or less varied by adjusting the stop 21 to regulate the extent of movement of the detent 12. As the escapement ratchet-wheel 8 advances step by step the ribbon-spools are correspondingly actuated, as previously described.

The construction and operation of my type-writing machine will now be readily understood upon reference to the foregoing description and the accompanying drawings, and it will be obvious to those skilled in the art that more or less change may be made in the construction and arrangement of the component parts thereof without departing from the spirit of my invention.

Having thus fully described my invention, what I claim as new, and desire to secure by Letters Patent, is—

1. In an escapement mechanism for type-writing machines, the combination with an escapement-wheel; of an oscillating member arranged at one side of the plane of the escapement-wheel and comprising opposite branches, and a part arranged substantially midway between the branches, one of the branches having a detent for co-operating with the escapement-wheel, and a second de- 130

tent comprising a radial arm pivoted to the part arranged between said branches, and a segmental head slidably engaging the other of said branches, the radial arm being interposed between said part and the opposing side of the escapement-wheel, and the segmental head having a detent for coöperating with the escapement-wheel, substantially as and for the purpose specified.

10 2. In an escapement mechanism for type-writing machines, the combination with an escapement-wheel; of an oscillating member arranged at one side of the plane of the escapement-wheel and comprising opposite branches and a part arranged substantially midway between the branches, one of the branches having an offset portion extending into the plane of the escapement-wheel, a detent provided on the offset portion for coöperating with the escapement-wheel, and a second detent comprising a radial arm pivoted to the part arranged between said branches, and a segmental head slidably engaging the other of said branches, the radial arm being interposed between said part and the opposing side of the escapement-wheel, and the segmental head having an offset portion extended into the plane of the escapement-wheel, substantially as and for the purpose set forth.

30 3: In an escapement mechanism for type-writing machines, the combination with an escapement-wheel; of an oscillating member provided with a branch arranged substantially concentric with the escapement-wheel, means for oscillating said member, and detents carried by the oscillating member and coöperating with the escapement-wheel, one detent being pivoted to the oscillating member substantially in alinement with the axis of the escapement-wheel and comprising a radial arm arranged at one side of said wheel, and provided with a segmental

head opposed to the concentric branch of the oscillating member and having one end 45 formed with an offset portion movable in the plane of the escapement-wheel said offset portion forming the part of said detent engaging the escapement-wheel, substantially as and for the purpose described.

4. In an escapement mechanism for type-writing machines, the combination with an escapement-wheel; of an oscillating member having a portion thereof movable at one side of the plane of the escapement-wheel, 55 and provided with opposing branches arranged substantially concentric to the escapement-wheel, one branch having an offset portion movable in the plane of the escapement-wheel and the other having a lateral extension in said plane, detents coacting with the escapement-wheel, one detent being fixed to said offset portion and the other comprising a radial arm at one side of the escapement-wheel pivoted at one end to the 60 oscillating member substantially in alinement with the axis of said wheel, and a segmental head opposed to the branch having a lateral extension and formed at one end with an offset portion movable in the plane of the 70 escapement-wheel toward and from said extension and provided with the face of said detent engaging the escapement-wheel, and a spring for moving the pivoted detent toward said extension, substantially as and for 75 the purpose described.

In testimony whereof I have hereunto signed my name, in the presence of two attesting witnesses, at Ilion, in the county of Herkimer, in the State of New York, this 11th 80 day of July, 1904.
